UNITED STATES PATENT OFFICE.

FREDRICK REICHWEIN, OF NEW YORK, N. Y.

HOT-DINNER PAIL.

SPECIFICATION forming part of Letters Patent No. 268,534, dated December 5, 1882.

Application filed April 10, 1882. (No model.)

To all whom it may concern:

Be it known that I, FREDRICK REICHWEIN, of the city, county, and State of New York, have invented a new and useful Improvement 5 in Hot-Dinner Pails, of which the following is a full, clear, and exact description.

Reference is to be had to the accompanying drawings, forming part of this specification, in which similar letters of reference indicate corresponding parts in all the figures.

Figure 1 is a sectional side elevation of my improvement. Fig. 2 is a sectional end elevation of the same. Fig. 3 is a sectional end elevation of the lamp. Fig. 4 is a bottom view 15 of the lamp. Fig. 5 is a sectional side elevation of a cooking-pan.

The object of this invention is to promote the convenience of those carrying a dinner or lunch with them, and also to facilitate the 20 warming or cooking of such dinner or lunch.

A represents the body of the pail, which is made rectangular in form, and has a flange, B, around the edge of the bottom to serve as a foot. The flange or foot B has numerous holes 25 formed in it to allow air to pass in beneath the bottom of the body A.

To the body A, at a little distance from its top, is attached a horizontal partition, C, forming a compartment, D. The space below the 30 partition C is divided by a partition, E, into two unequal compartments, F G. Access to the larger compartment, F, which serves as a provision-chamber, is had through an opening, H, in the end of the body A. The opening H is closed by a door, I, which for convenience I prefer to hinge at its lower edge. The door I is fastened when closed by a button, J, or other suitable fastening. The smaller compartment, G, is made open at the bottom, and 40 is intended to receive the lamp K, to the bottom of which are attached spring-latches L, to engage with slotted plates M or other catches attached to the body A and projecting downward within the foot B.

To the bottom of the lamp K are attached 45 downwardly-projecting flanges N, to serve as feet to support the lamp K when detached from the body A, and as a handle for convenience in inserting and removing the lamp. The sides 50 of the lamp project beyond its ends, so as to fit into the chamber G and to form chambers at

one end of the lamp, to receive the button O, attached to the stem of the wick-wheels P, and the cap Q, which closes the filling-aperture at the other end of the said lamp. 55

Access may be had to the button O, for raising and lowering the wick without detaching the lamp, through an opening in side of the body A, which opening can be closed by a slide, R. The wick-wheels P are placed within 60 the lamp K, and their stem passes through a stuffing-box, S, in the end of lamp K, to guard against any leakage of oil. The wick-tube T extends down into the interior of the lamp K, and the lower edge of one side of the said tube 65 projects and is secured to the bottom of the said lamp, the lower part of the other side of the said tube being cut away for the passage of the wick. The lamp K is made narrower than the chamber G, so that air to support 70 combustion can pass up freely through the side parts of the said chamber. The lamp K is covered upon its top, sides, and bottom, with a layer, U, of asbestos felt or other suitable incombustible and non-conducting material, to prevent the lamp from becoming 75 heated. The felt U is kept in place and protected from injury by being covered with a thin sheet-metal casing, V. The wick-tube T is also covered nearly to its upper end with 80 a layer, U', of asbestos felt, which is covered with a casing, V', of sufficient size to inclose the wick-tube and its felt covering. With this construction the outside of the lamp K and its wick-tube are fully protected from the heat. 85

W is a guard of perforated sheet metal or wire-gauze, the middle part of which has a slot formed in it to receive the wick-tube. The side parts of the guard W are bent downward and then inward, and their edges are soldered 90 or otherwise secured to the top of the lamp. The length of the guard W is equal to the length of the chamber G, and the width of the horizontal middle part of the said guard W is equal to the width of the said chamber G, 95 so that the guard W, in connection with the spring-latches L, will prevent all movement of the lamp when in place. With this construction the air to support combustion must pass twice through the guard W before it reaches 100 the point of combustion, so that the lamp will not be liable to be blown out by the wind.

Above the upper end of the wick-tube T is placed a cone, X, the lower edges of which extend outward horizontally, and are attached to the wall of the chamber G.

5 Y is a sheet-metal chimney, the lower end of which surrounds the cone X and rests upon the base of the said cone. The upper end of the chimney Y is connected with an opening in the partition C, through which the heated 10 products of combustion pass into the heating-chamber D near one end. In the wall of the body A, at the other end of the chamber D, is formed an opening, D', through which the heated products of combustion escape into the 15 air after passing through the entire length of the said chamber.

The heating-chamber D and the part of the lamp-chamber G above the guard W are lined with asbestos felt Z or other suitable incom- 20 bustible and non-conducting material. The felt Z can be secured in place by points cut out of the wall of the body A and the chimney Y and bent down over the said felt, or by other suitable means.

25 In the side walls of the heating-chamber D are formed apertures *a* to allow the condition of the flame to be seen, so that the wick can be properly adjusted without removing the lamp.

30 *b* is a boiler for making coffee or boiling other liquids, and which is made with a downward and upward bulge and a flange, as shown in Figs. 1 and 2, so that its edge will rest upon the upper edge of the body A, and the said boiler will serve as a cover to the heating-chamber D. With this construction the lower 35 part of the boiler *b* projects into the heating-chamber D, and is exposed to the heated products of combustion as they pass through the 40 entire length of the heating-chamber D from the chimney Y to the opening in the end wall of the said chamber D, so that the contents of the boiler *b* will be heated very quickly. The boiler *b* is provided near one end of its 45 upper side with an opening closed with a screw-cap, *c*, for convenience in filling and emptying the said boiler. The boiler *b* is also provided with a handle, *d*, for convenience in handling it.

To lugs *e*, attached to the upper edges of the 50 sides of the body or shell A, are attached the ends of two bails, *f*, the middle parts of which are passed through the perforation of the hand-piece *g*, to form a convenient handle for carrying the pail. The pail is also provided with

a rectangular pan, *h*, of such a size that its 55 wired edges will rest upon the wired upper edges of the body A, so that the said pan can be used for frying meat and eggs, warming potatoes, and doing other cooking. The pan *h* is provided with a handle, *i*, which is bent 60 downward near its inner end, and is hinged at its inner end to the stiffening-wire in the edge of the said pan, so that the said handle can be turned down into the interior of the pan *h*, as shown in Fig. 1, for convenience in packing it 65 into the pail A for carriage. The stiffening-wire of the pan *h*, at the point where the handle *i* is hinged to it, has an upwardly-projecting loop, *j*, formed in it, to serve as a stop to the handle *i* when lifting the said pan by its handle. 70

Having thus fully described my invention, I claim as new and desire to secure by Letters Patent—

1. A hot-dinner pail constructed substantially as herein shown and described, and 75 consisting of the shell A, divided into three compartments, D F G, by two partitions, C E, the lamp K, provided with spring-latches L and screen W, and the boiler *b*, as set forth.

2. The combination, with the lamp having 80 at the bottom spring-latches L; and a pail having the foot B, of the plates M, attached to the pail and projecting down within the foot, as and for the purpose described.

3. In a hot-dinner pail divided into compartments by partitions, the combination, with the heating-compartment D and the upper part of the lamp-compartment G, of an incom- 85 bustible and non-conducting lining, Z, substantially as herein shown and described, 90 whereby the provision-chamber F is kept from becoming unduly heated, as set forth.

4. The combination of the chamber G of a lamp having its sides projected beyond its ends, the wheels P, having button O, and the 95 cap Q, as and for the purpose set forth.

5. In a hot-dinner pail, the combination, with the lamp K, the wick-tube T, and the lamp-chamber G, of the screen W, having its side parts bent inward and downward, substan- 100 tially as herein shown and described, whereby the flame is prevented from being blown out by the wind, as set forth.

FREDRICK REICHWEIN.
